APPARATUS FOR TWISTING FIBROUS STRANDS

Roy E. Smith, Anderson, S.C., and Francis C. Skalko, Lincoln, R.I., assignors to Owens-Corning Fiberglas Corporation, a corporation of Delaware
Filed Aug. 24, 1962, Ser. No. 219,273
2 Claims. (Cl. 57—58.83)

This invention relates to apparatus for producing twisted strands or yarns of fibrous materials, and more particularly to method and apparatus for twisting strands or yarns made either of continuous or staple glass fibers.

The production of strands and yarns of continuous glass fibers suitable for weaving involves first the manufacture of a forming package. This involves the attenuation of a plurality of streams of molten glass, produced by a bushing, to form filaments that are gathered together just after application of a liquid binder and size, into a single strand. The strand is wound wet and at high speed upon a rapidly rotated moisture-resistant tube. The rapid winding provides the force for attenuating the glass streams into the fine fibers.

At this point of production, this so-produced forming package is highly saturated with moisture and although requiring drying to a degree, is nevertheless maintained at a high moisture level to preserve strand integrity and keep the plurality of 200+ filaments positively bonded together in the single strand.

As a result of the required moisture content to preserve strand integrity, rewinding from the forming package for twist and subsequent ply into balanced yarns for weaving has in the prior art required tangential take-off. This requires rotating the forming package on the creel of the twisting frame and feeding the strand down to the subjacent ring and traveler twister for rewind package formation. Tangential strand take-off from the forming package, as is well-known, requires that the forming package be rotated about its axis as the strand is fed downwardly to the ring and traveler where the twist is applied. However, the nature of the package limits the rate at which tangential removal can be made. Thus, the package is a dynamically unbalanced mass having a substantial amount of difficult-to-control kinetic energy at even relatively low rotational speeds; this unbalance results in vibration, strand breakage and similar problems.

Further, due to the unbalance of the package, strand will feed from one side more rapidly than from the other because of varying speed of rotation; this causes "loping"; that is, the strand will overrun or overfeed intermittently, providing slack and then when it slows down, the strand will be snapped taut, resulting in strand breakage, particularly at higher speeds. Also, this loping or slack development results in loop formation in the plied yarn. As is well-known, yarn strength at the point of and beyond the free end of the loop is substantially nil. Thus, the rotating forming package strand take-off for purposes of rewinding and twisting has a number of drawbacks.

Accordingly, it would provide a valuable step forward in the art if a method and apparatus could be provided wherein the rewinding of strand could be speeded and at the same time wherein the defects of loping, snapping with strand breakage, and looping inherent in this prior art procedure could be overcome.

It is accordingly an important object of the present invention to provide an apparatus for rewinding and twisting strands of both continuous and staple glass fibers.

A further object is to provide an apparatus for rewinding and twisting strands of glass fibers wherein the package is retained in a stationary position.

A further object is to provide an apparatus for rewinding

2

ing and twisting strands of glass fibers wherein rewinding speeds are substantially increased over the prior art and production is boosted as contrasted to the low processing speeds are substantially increased over the prior art and processing speeds.

10 A further object is to provide an apparatus for rewinding and twisting strands of glass fibers from a forming package wherein the rewind speed is substantially increased over the prior art, but at the same time, the processing difficulties of the prior art are overcome by utilizing a stationary forming package and taking strand off over end of the package for an initial turn.

15 A further object is to provide apparatus for rewinding strands of continuous and staple glass fibers from either flat or barrel build packages optionally using a free-running take-off traveler.

20 Other objects of this invention will appear in the following description and appended claims, reference being had to the accompanying drawings forming a part of this specification wherein like reference characters designate corresponding parts in the several views.

FIGURE 1 is a schematic-type view, partly in section, illustrating one form of method and apparatus of the invention;

25 FIGURE 2 is a longitudinal sectional view of a second type of top-twister apparatus of the invention;

FIGURE 3 is a schematic-type view analogous to FIGURE 1, illustrating an inverted version of one form of top-twister apparatus of invention; and

30 FIGURE 4 is a schematic-type view of apparatus and method of invention for feeding pre-twisted strands to a beamer in accordance with the invention.

35 Before explaining the present invention in detail, it is to be understood that the invention is not limited in its application to the details of construction and arrangement of parts illustrated in the accompanying drawings, since the invention is capable of other embodiments and of being practised or carried out in various ways. Also, it is to be understood that the phraseology or terminology employed herein is for the purpose of description and not of limitation.

PERSPECTIVE VIEW

45 Briefly, the present invention encompasses apparatus for rewinding strands, particularly of glass fibers, from either flat-build or barrel-build forming packages. More importantly, the present invention provides highly accelerated rewinding from a stationary package to apply twist for purposes of subsequent ply.

50 By the present invention a top rewind apparatus is employed which holds the forming package stationary as contrasted to the present rotating creel. Also in the present invention the strand or yarn is removed over end, then directed in a reverse manner axially through the package and then turned about the package to provide a double twist, followed by subsequent twisting by ring and traveler, giving a multiple twist wherein only a single twist was capable of being imparted heretofore by the prior art.

60 It is an unusual aspect of the invention that problems heretofore encountered in over end take-off of barrel-build packages have been solved in accordance with the present invention. Therefore, as shown in FIGURE 2 of the drawings and as will be fully described, rapid over end take-off from a barrel-build package is provided, which has not been possible heretofore. This is particularly advantageous when using a high moisture content package to provide strand integrity, and with multiple twist not heretofore possible in such a rapid and efficient manner.

70 In another aspect, the present invention relates to a highly compact apparatus for producing multiple twist

strand, with substantial advance over the prior art, where in a stationary forming package is utilized at the top of a twister frame instead of a rotating package creel, and wherein strand during rewinding and twisting is drawn downwardly to provide unidirectional process flow without frictional forces encountered by direction reversal.

In a still further aspect of the invention, as shown in FIGURE 4, yarn is twisted during over end take-off from a stationary forming package and fed in a pre-twisted condition directly to a beamer without the presently-required rewinding.

In view of the foregoing introductory comments, a full explanation of each of the embodiments of the present invention now follows:

THE EMBODIMENT OF FIGURE 1

As shown in FIGURE 1, strand from a forming package, held in the non-rotated position at the creel position of a rewinding frame, is provided with a double twist after which it is subsequently fed downwardly to a normal milk bottle build package, at which point subsequent twists are provided. Thus, the numeral 10 represents a support member of a twister frame, to which a bracket 12 is fastened as by welding at 11. To the top surface of the bracket 12, there is mounted as by bolting at 14 a top twister unit 16. More particularly, the twister unit 16 includes a base member 18, which includes a thrust bearing socket 20 and a rotary bearing 22, both being formed at the ends of a tubular support 24, extending perpendicularly from the aforementioned base 18.

Adapted to be power-driven and mounted upon the base 18 in the bearings 20 and 22 there is an intermediate spinner member 26, comprising a center shaft 28, formed coaxial to a tubular drive hub 30, about which a belt 32 is wrapped in driving relation. A retainer flange 34 extends radially at the bottom end of the tubular drive hub 30 for guidance of belt 32. The upper part of the intermediate spinner member 26 includes a coaxial tubular strand guide 36, having a hollow interior and supported at its base end in a central body portion 38 of the intermediate spinner member 26.

A strand outlet passage 40 extends radially outwardly, joining with the hollow interior of the tubular strand guide 36 at its base, and cooperating with upturned flange 42, which serves as a feed-off lip of smooth contour.

The package support is designated 44 and comprises at its bottom portion a basket-like member 46 or basket-like annular wall 46 with an annular cavity 48 therein to retain a weight 50.

Coaxially, the unit includes a tubular bearing housing 52 with lower and upper bearings 54 and 56, mounted on the exterior of the tubular strand guide 36 previously discussed. From the foregoing, it will be understood that the package support 44 can float upon the intermediate spinner member 26.

Upwardly from a radial stiffener wall 58 and coaxially outwardly from the tubular bearing housing 52, there extends upwardly and coaxially a tubular package support 60. Onto this package support 60, a flat build forming package 61 of strand is positioned in slip-on relation.

It should be noted that a tensioning device of known configuration is positioned either within the strand guide 36 or the outlet passage 40, in this and the subsequent embodiments.

After a package 61 is placed in position, a plug end 64 is applied by slidably inserting it concentrically within the upper end of the tubular package support 60. For this purpose, the plug end 64 has a radial flange 66 to abut the top end of support 60. The plug end 64 is of tubular configuration and stepped downwardly in size at the top end to form a fiber entrance aperture 68.

With the plug end 64 in place, a strand end 70 is removed from the package 61 and threaded coaxially downwardly through the unit, as by a small feed tube or other probe device, and pulled through the strand outlet passage 40 to be directed upwardly through the first feed loop 72,

thence to the second feed loop 74, to reverse direction 90° or a total of about 180°, and then descend perpendicularly to a conventional ring and traveler twister 76, including its guide loop 78.

Intermediate the second feed loop 74 and the guide loop 78 there is provided a pair of nip rolls 75 which are driven at an appropriate speed. The strand 70 is run between the rolls 75 which provide the moving force for the strand.

Twister 76 comprises a spindle support shaft 80 fastened in a support member 82 and extending upwardly therefrom. A rotatable spindle 84 is journaled upon the support shaft 80 and the upper tubular portion thereof is configured to receive a tube 86 of conventional structure.

The lower portion of the spindle 84 is formed as a flat belt pulley 88, over which a belt 90 is lapped in driving relation.

Mounted on a vertically moveable support 92, there is provided a rotary ring and traveler assembly 94, comprising a ring member 96 and a traveler of semi-loop configuration 98. Support 92 is adapted for vertical movement as indicated by the arrow 100.

In operation, the ring and traveler assembly 94 is moved vertically while the strand 70 is fed downwardly through the guide loop 78, thence through the traveler 98 and onto the tube 86 to form a package 102 by rotation of the tube 86 through the driving belt 90. Rotation of the package 102 causes the traveler 98 to whirl upon the ring 96 and thereby imparts twist in accordance with the rate of lineal speed of the strand 70 onto the package. Vertical movement of the ring and traveler builds the package 102 to a suitable profile.

OPERATION SUMMARY OF FIGURE 1

From the foregoing, it will be evident to one skilled in the art that the forming package 61 positioned on the tubular support 60 of the package support 44 is retained in non-rotatable relationship by gravitational pull on the weight 50.

As the strand 70 balloons off at 104 in its over end travel from the package 61 and reverses to concentric lineal passage through the package, a first twist is applied. Upon departure from the strand outlet passage 40, the strand balloons as at 106 outwardly of the previously mentioned balloon 104 and a second twist is imparted. Thus, a double twist is provided in merely getting the strand off the package in accordance with the present invention. The guide eyes 72 and 74 and 78 then direct the strand to the package 102 where additional turns are applied.

From the foregoing it will further be obvious that extremely high rates of rewinding and twisting are obtainable in accordance with the present invention by virtue of the fact that the package is not rotated and the dynamic unbalances inherent therein are nullified. Thus, a valuable step forward in the art is provided in accordance with the present invention, improving economies of operation, both by accelerating the winding speeds and secondly and equally as importantly by providing a total desired twist in a single operation, without requirement of a second winding, which is an extremely expensive and time-consuming operation and often wasteful because of strand breakage during end finding.

THE EMBODIMENT OF FIGURE 2

While over end take-off of strand has heretofore been capable of accomplishment at least to a degree, from flat-build packages, i.e. truly cylindrical packages, even with an appreciable moisture content in the fiber for strand integrity, such take-off from a barrel-build package has not been previously accomplished.

In accordance with the FIGURE 2 embodiment of the present invention, this problem has now been solved, and extremely rapid rates of rewinding and multiple twisting with either flat-build or barrel-build packages is provided within the logical extension of the present invention.

As shown in FIGURE 2, therefore, over end take-off from a barrel-build package is provided. In accordance with this embodiment of the invention, the top twister is essentially of the same general configuration of parts as the equivalent item of the FIGURE 1 embodiment; therefore, similar elements will receive the same reference numerals. Thus, the unit comprises a base 18, bolted or otherwise fastened to a suitable support as in FIGURE 1, and defining bearings 20 and 22. Drive by belt 32 is the same.

The intermediate spinner member 26 is also the same, with a center shaft or spindle 28, rotatable within the bearings 20 and 22, and including the tubular strand guide 36 extending coaxially and upwardly therefrom.

The package support 120, however, is modified from the showing of FIGURE 1 by having the basket-like wall 122 extend upwardly beyond the radial intermediate wall 58 to support a ring 124 intermediate the ends of the package 62. The ring carries a traveler 126. The plug end 64 is as described above, having a radial flange 66 and fiber entrance aperture 68.

The weight 50 retains the package support 120 in non-rotatable relation upon the intermediate spinner member 26. Here, it will be noted, a barrel-build package is being rewound. Thus, with the package 62 in position and the plug end 64 in retaining arrangement thereto, a fiber end 70 is threaded through the traveler 126 and upwardly to the fiber entrance aperture 68 where it is again threaded as by a probe, axially through the tubular strand guide to the strand outlet mouth 40, and upwardly and around to the first feed loop 72.

SUMMARY OPERATION OF THE FIGURE 2 EMBODIMENT

Operation of the FIGURE 2 embodiment comprises belt drive rotation of the intermediate spinner member 26, whereby with draw-off of the strand by suitable pulling device such as the conventional twister 76 in FIGURE 1, the strand 70 is caused to first balloon as at 104, and pass coaxially through the package 62, imparting a first twist, thence radially outwardly through the delivery mouth 40 to re-balloon as at 106 to provide a second twist. Note the manner in which the ring and traveler cause the strand 70 to be lifted radially outwardly from the periphery of the barrel-build package.

Thus, from the foregoing it will be understood that the strand can be picked off over end from a barrel-build package at a much increased rate of speed over the conventional tangential take-off system now employed, because dynamic unbalance forces do not limit the rate of take-off; additionally, the present system provides a double twist as the strand leaves the package, whereas according to the prior art no twist at all was provided at the point of departure.

THE EMBODIMENT OF FIGURE 3

By proceeding in accordance with the schematic showing of FIGURE 3, it will be obvious to those skilled in the art that an improved straight-line flow of strand is provided at a high rate of rewinding and twisting in accordance with the present invention.

In describing this aspect of the invention, similar reference numerals will be applied as above where like parts are designated.

Thus, the top twister utilized in this embodiment is also mounted on a support member 10 of a creel of a twister frame, secured as by welding as at 11. In this embodiment it will be noted that the support bracket 12 is of essentially the same angular construction, but inverted, and that bolts 14 are used to retain the base 140 of the inverted twister 142 in attached relation to the inverted bracket element 12.

In this embodiment of the invention, the base 140 is different from the corresponding unit 18 of the embodiments of FIGURES 1 and 2. Thus, instead of a thrust

bearing 20 in FIGURES 1 and 2, a tension bearing is required as at 144. This comprises an annular bearing member and retainer 146, pressed against a shoulder 148, formed within the hollow interior of the tubular support 150 of the base 140.

An annular retainer and bearing member 152 is inserted behind the annular bearing member and retainer 146, as by threading, to complete the tension bearing 144.

Member 146 absorbs both radial and axial thrust from the shaft end 154 of shaft 156 and radial bearing 158 at the bottom end of tubular support 150 supports the bottom end of shaft 156. The intermediate spinner member, corresponding to the numeral 26 of FIGURES 1 and 2, is here designated 160 because of somewhat different configuration in the fact that the shaft 156 for assembly purposes must be removably secured into the intermediate spinner member, as indicated at 162 in FIGURE 3.

Remaining aspects of the inverted top twister 142 are similar to those shown in FIGURE 1, including package support 44 comprising tubular package support 60, upon which a flat build package 61 is mounted, with plug end 64 having radial flange 66 and fiber entrance aperture 68. A slight departure will be noted in the weight 166, provided for non-rotation of package support 44.

By this embodiment of the invention, it will be noted that one end guide eye 164 is utilized instead of two guide eyes 72 and 74 in FIGURE 1. Thus, straight line flow is provided, reducing friction of reversal of strand, as by the second eye 74, FIGURE 1.

Loading of the top twister 142 of FIGURE 3 is accomplished by inserting the package 61 onto the tubular support 60 of the package support 44, selecting a strand end 70, feeding the same axially through the unit and out through the strand outlet throat 40, around and down to the guide eye 164. From the guide eye 164, the strand 70 is passed downwardly through nip rolls 75 to the guide loop 78 of twister 76, comprised of the same parts previously described.

In operation, the fiber strand 70 first balloons as at 104, reverses coaxially through the package 61, providing a first twist, then reversing again to balloon at 106 prior to entrance to the guide eye 164, providing a second twist. From the guide eye 164 flow is directly downwardly to the aligned eye 78. Then the strand again balloons at 108 prior to entry through the traveller 98 onto the package 102.

By proceeding in accordance with the apparatus and method of FIGURE 3, essentially the same end result is provided as in FIGURES 1 and 2. However, straight line strand flow is provided after the second twist is applied without turning the corner as at 74 in FIGURE 1. Thus, slightly increased operating efficiencies are provided in accordance with this aspect of the invention.

The embodiment of FIGURE 3 can also be modified to incorporate the ring and traveller modification of the top twister shown in FIGURE 2. Such modification is to be included within the scope of the present disclosure.

THE EMBODIMENT OF FIGURE 4

FIGURE 4 illustrates application of the present invention to a beamer, providing double twist before the strand is applied to the beamer package, consisting of several hundred ends of strand.

Accordingly, a base member 170 is suitably supported in space, such as on a beamer creel, and the twister 16, the same as in FIGURE 1, is applied thereto by suitable attachment means, not shown. A belt 32 laps the drive hub 30 to rotate the intermediate spinner member 26. The strand 70 balloons as at 104 and then enters the fiber strand entrance aperture 68, passing coaxially through the flat-build package 61, thence out the strand outlet passage or throat 40, ballooning again as at 106 as it passes upwardly around the unit.

At a point 172 coaxially above the package 61, the

strand 70 passes through a guide 174, by which it is directed upwardly to a tension disc 176, and then passes horizontally in the arrow 182 direction to the beamer pressure roll 184. By means of a suitable traverser, not shown, the strand 70 is directed over roll 184 and thence onto the package 186, carried upon the beam 188 of a collet 190 that provides a rotating drive force. The beam 188 carries a beam tube 192 upon which the package 186 is formed.

From the foregoing, it will be evident that when the strand 70 enters the fiber entrance aperture 68, a first twist is applied by means of the balloon at 104. After passing axially through the package 61, the strand 70 then reverses direction, passing out of the strand outlet throat 40, ballooning again at 106 on its way to the guide eye 174; thus a second twist is imparted. Passing from the guide eye 174, the strand is properly tensioned at 176 and thence flows to the package 186.

In the present description of beamer operation, it is to be understood with regard to FIGURE 4 that only one twister 16 is shown, whereas the actual production of a beamer package involves the use of a plurality of up to 1,000 or more twisters 16 feeding strands 70 to the package. A typical package may have a core of about 12" diameter by about 54" length to produce a finished package of about 32" diameter and about 54" length.

The showing here regarding the beamer is somewhat schematic for clarity. A beamer package is normally held on gudgeons or stub shafts which fit on the driving head of the beamer frame, and either one or both ends of the beamer may be driven. In the event only one end is driven, the other end is supported in a suitable anti-friction bearing.

An important advantage of course inherent in the method and apparatus disclosed in FIGURE 4 resides in the fast over end take-off from the package. Secondly, a double twist is applied as sharply contrasted to the practice of the prior art where first a milk bottle build package would have to be produced. Thereafter, this was rewound into a beamer-type package, thus entailing a two-step operation. In accordance with the present embodiment, manufacturing costs are cut by more than half, with more than a doubling in product output per unit time because of the fact that manual handling, loading and end finding are omitted. Additionally, much higher speed operation is provided by take-off from a stationary forming package directly to the finished beamer package consisting of several hundred ends drawn into a common package.

50

EXTENDED SCOPE OF INVENTION

From the foregoing, it will be evident that anti-friction bearings provided in accordance with known engineering principles are utilized, with lightweight, high-strength materials for rapid rotational speeds, typified by the phenolic resins, suitably reinforced.

While the weight 50 in FIGURES 1 and 2 and 166 in FIGURE 3 has been shown as the means whereby the forming package is retained in a stationary position, it is to be included within the scope of the invention to use magnetic dampers for this purpose if desired.

While the intermediate spinner member 26 of FIGURES 1, 2 and 4, and 160 of FIGURE 3, has been shown as being power driven, because of the primary desire in the present invention to provide uniformity of twist through the running length of the strand, it is to be considered within the scope of the invention to provide a slight modification at this point. Thus, the intermediate spinner member may be free-running for reinforcement staple yarn where uniformity of twist is of no consequence.

This type of fiber strand can also be subsequently plied, and will make a yarn satisfactory for plastic reinforcement where uniformity is not so critical as in weaving yarns. In the logical extension of invention, therefore,

the intermediate spinner member can be either driven or free-running.

ADVANTAGES OF THE PRESENT INVENTION AND CONTRIBUTION TO THE ART

From the foregoing, it is believed obvious that the following advantages are provided by the present invention:

(1) Higher processing speeds by use of a stationary feed-off or forming package;

(2) Reduced processing costs by omitting at least half of the twisting steps formerly required for twisting, with a similar reduction of operator time, supervision, employee benefits, etc.;

(3) More compact processing equipment with less vibration to the creel of the twister frame, by utilization of a stationary feed-off or forming package;

(4) Novel processing procedure for barrel-build package, utilizing a novel primary ring and traveler to lift the strand off the package;

(5) Novel inverted package processing with straight line flow characteristics;

(6) Novel formation of a beamer package directly from a forming package by applying twist to the strand as it is fed off the forming package, then tensioning and directing to the beamer package; and

(7) Loping, looping and breakage from snapping are overcome by constant strand pull.

The economies of processing alluded to above provide a definite contribution to the art, and will enable the fiber processor to improve his cost picture while being able to simultaneously reduce the consumer price, thereby benefiting mankind and providing greater utilization of synthetic fibers.

We claim:

1. In a system for rewinding continuous strand, a base supported in space and having spaced coaxial bearings with the axis generally vertically disposed and canted slightly from true vertical, an intermediate spinner member having a coaxial shaft carried in said base bearings and having a strand guide tube coaxial thereto and operably connected with a radially opening throat to direct strand radially outwardly, a bowl-shaped package support journaled on the strand guide tube of the intermediate spinner member, weight means in said package support to prevent rotation thereof, a package of strand carried coaxially on said package support, an annular guide in the free end of said package support and having an eye coaxial to the package to direct the strand from the periphery of the package as a first free balloon around the free end of the package and axially through the package and into the interior of the intermediate spinner member and into the strand guide tube and throat of the intermediate spinner member, and the throat being effective to direct the strand radially from the axis of the package outwardly to a second free balloon entirely surrounding the package and the first free balloon, a first strand guide coaxial to and spaced from the free end of the package, a second strand guide offset from the first strand guide and in a generally horizontal plane with said first guide, a pair of abutting pull rolls beneath said second guide, a third strand guide beneath said pull rolls, and a ring and traveller package winding device beneath said third strand guide.
2. In a system for rewinding continuous strand, a base supported in space and having spaced coaxial bearings thereon, with the axis generally vertically disposed and canted slightly from true vertical, an intermediate spinner member having a coaxial shaft

rotatably carried in said base bearings and having a strand guide tube coaxial thereto and operably connected with a radially opening throat to direct strand radially outwardly,
 a bowl-shaped package support rotatably journaled on 5
 said strand guide tube of said intermediate spinner member,
 means to prevent rotation of said package support,
 a package of strand carried coaxially on said package support,
 10 an annular guide member of elongated tubular structure positioned in the free end of said package support and having a guide eye positioned coaxial to said package to direct said strand from the periphery of said package as a first free balloon around the free end of 15 said package and axially through said package and into the interior of said intermediate spinner member and into said strand guide tube and said throat of said intermediate spinner member, and said throat being effective to direct said strand radially from 20 the axis of said package outwardly to a second free balloon entirely surrounding said package and said first free balloon,
 a first strand guide coaxial to and spaced from the free end of said package,
 25 a second strand guide offset from said first strand guide and positioned in a generally horizontal plane with said first strand guide,

a pair of abutting pull rolls positioned beneath said second strand guide,
 a third strand guide positioned beneath said pull rolls, and a ring and traveler package winding device positioned coaxially beneath said third strand guide.
